UNITED STATES PATENT OFFICE.

JOHN P. POMEROY, OF GREAT BARRINGTON, AND HENRY M. VAN DEUSEN,
OF WESTFIELD, MASSACHUSETTS.

DESIGN FOR A WHIP-LOAD.

SPECIFICATION forming part of Design No. 32,742, dated May 29, 1900.

Application filed April 13, 1900. Serial No. 12,775. Term of patent 14 years.

To all whom it may concern:

Be it known that we, JOHN P. POMEROY, residing at Great Barrington, in the county of Berkshire, and HENRY M. VAN DEUSEN, residing at Westfield, in the county of Hampden, State of Massachusetts, citizens of the United States, have invented and produced a new and original Design for a Whip-Load, of which the following is a specification.

10 Our invention relates to whip-loads.

In the accompanying drawings, Figure 1 is a front view of our design. Fig. 2 is a central longitudinal section thereof.

Our design consists of a whip-load having 15 upon its outer surface a series of rings connected together by their edges and one of the rings connected to a flattened ball or sphere. The outer contour of these rings is formed of a series of circular arcs, the centers of which lie near the intersections of the 20 axes with the planes of junction of the con-

tiguous rings. The rings gradually increase in width as they approach the ball, and a circular aperture is formed centrally through the inner axis of the flattened ball.

25

The whip-load is slightly tapering in contour, is hollow, and the socket therein is of equal diameter from the shoulder at the top of the flattened ball or sphere to the top edge of the load.

30

What we claim is—

The design for a whip-load, as shown and described.

In testimony whereof we have hereunto set our hands in presence of two subscribing witnesses.

JOHN P. POMEROY.
HENRY M. VAN DEUSEN.

Witnesses:

AMY N. STILES,
M. A. WILLIAMS.
